HIRAM WILSON, OF YOUNTVILLE, CALIFORNIA, AND ONE-FOURTH TO JOHN P.
VISSER, OF SAN FRANCISCO, CALIFORNIA.

REVOLVING SUSPENSION-RACK.

1,150,282.

Specification of Letters Patent. Patented Aug. 17, 1915.

Application filed July 2, 1914. Serial No. 848,702.

To all whom it may concern:

Be it known that I, WILLIAM H. MARTIN, residing at Yountville, in the county of Napa and State of California, have invented 5
certain new and useful Improvements in Revolving Suspension-Racks, of which the following is a specification.

This invention has reference to improvements in that class of racks or supporting 10 means more especially designed for use upon trucks, and it is more particularly intended for the transportation of such articles requiring careful handling and to be held from exposure to the elements during trans- 15 portation.

Among other objects, my invention has for its purpose to provide an improved construction of revolving suspension rack in which is included a plurality of independent 20 compartments so arranged and constructed that the goods or articles to be transported may be conveniently and quickly placed therein or removed therefrom.

With other objects in view that will hereinafter be explained, the invention consists in the peculiar construction and novel arrangement of parts set out in the following description, specifically pointed out in the appended claims and illustrated in the accompanying drawing, in which:

Figure 1 is a perspective view of my invention, the same being shown operatively mounted upon an auto truck. Fig. 2 is a side elevation partly in section. Fig. 3 is a 35 horizontal section of one of the compartments and portions of other compartments. Fig. 4 is a horizontal section of the complete rack and illustrates more particularly the metallic base or floor construction.

40 In the practical construction, my present form of revolving suspension rack includes a central mast 1, which may be solid metal or be hollow with a hard wood filler, and the lower end thereof is reduced to form a 45 foot portion 11 for fitting a socket 20 in a base plate fixedly joined with the lower end of the mast 1 and formed with a pendent stud 21 that passes down into an aperture 3 in the truck platform, as shown. The mast 50 1 is firmly braced by the diagonal stay bars 4 whose lower ends engage the truck platform and whose upper ends are secured to a collar 5 that is integral with or fixedly secured upon the mast, as shown. By reason

of mounting the mast in the manner stated 55 and shown, the said mast and its attached parts may be readily bodily removed from the truck as desired.

6 designates a sleeve rotatably mounted upon the mast and supported upon the collar 5, and 7 designates sweep arms that radiate from the said sleeve 6 and turn therewith.

The several sweep arms 7 are braced by hanger cables or rods 8 whose upper ends 65 are fastened to the eyes 9 pendent from a collar 12 rotatably supported upon the upper end of the mast. The lower ends of the rods 8 connect with rings 13 upon the outer ends of the several sweep arms 7. 70

14 designates a covering of canvas or other suitable material, which extends entirely over the rods 8 and forms a top closure for keeping rain and dust out of the several goods holding compartments presently again 75 referred to.

As shown in the drawings, my present form of revolving suspension rack includes a plurality of independent goods holding compartments, six being shown, and they 80 are constructed in the manner best shown in Figs. 2, 3 and 4 of the drawings, by reference to which it will be noticed that a hanger arm 16 is pendently supported from the outer end of each of the sweep arms and the 85 lower ends of the arms 16 are held spaced apart and braced by a hoop 17 to which the lower ends of the arms 16 are fixedly connected.

18 designates what I term the "inner 90 hangers" whose upper ends are made fast to the sweep arms near the inner or hub ends thereof.

19 designates a hoop that joins with the lower ends of the diagonal hangers and, as 95 will be readily understood from Fig. 2 of the drawings, the said hoop 19 is held far enough away from the mast braces so as to positively clear them.

30 designates wire mesh in the closure 100 doors 38—39, the said doors being located between the pendent outer hangers, and 31 designates a series of wire mesh partitions that form the sides of the several compartments. 105

32 designates a wire mesh covering that extends entirely over the inner faces of the diagonal hangers, and 33 designates a heavy

oil-cloth or linoleum covering that extends over the wire mesh covering 32, a similar covering 34 being also used on the front wall of each of the compartments.

5 The bottom 35 of my improved revolving rack is formed of strong sheet metal, the outer edge of which is bent up to form a flange 36, against which the outer hangers fit and to which they are made fast and the 10 said bottom has its outer edge supported upon the hoop that connects with the several outer hangers. The bottom plate 35 is also provided with an inner flange 37 that inclines outwardly and rests upon the inner 15 or diagonal hangers, as shown. The front wall of each of the compartments has hinged doors 38—39, the construction of which is best shown in Fig. 3.

40 designates a stay member that extends 20 lengthwise over the truck and connects the upper ends of the two masts and has its front end suitably connected with the truck body, as shown.

From the foregoing description, it is 25 thought the complete construction, the manner of use and the advantages of my invention will be readily understood by those skilled in the art to which it appertains.

What I claim is:

30 1. A revolving rack comprising a mast, a support on which said mast is mounted, stay bars extending forwardly from said support and converging toward said mast, a collar secured to the mast over the adjacent ends 35 of said stay bars, a sleeve rotatable on the mast and supported by said collar, sweep arms radiating from said sleeve in a horizontal plane, a peripheral ring connecting the ends of said sweep arms, a second collar 40 rotatably supported on the upper end of the mast, said first mentioned collar and said sweep arms being located in a plane below the upper end of the mast, hanger cables extending from said second collar downwardly and outwardly to support the 45 peripheral ring of said sweep arms, pendent hanger arms supported from the outer ends of each of said sweep arms, a ring connecting the lower ends of said pendent hanger

arms, inner hangers extending from the inner extremities of said sweep arms diagonally downwardly and outwardly in parallelism with said mast diagonal stay bars, a ring connecting the lower ends of said inner hangers, a platform connecting said inner hanger ring and said pendent hanger arm ring, said platform having an outer and inner annular flange, the outer flange extending parallel to and in proximity to said pendent hanger arms and the inner flange 60 extending parallel to and in proximity to said inner hangers, a screen fabric surrounding said inner hangers, screened radial partitions below said sweep arms and screen doors between said hanger arms, all being 65 arranged substantially as shown and for the purposes described.

2. A rack of the character described, comprising a central support adapted for being fixedly mounted upon a truck platform, and 70 bracing elements for supporting it on the said platform, a collar fixed on said central support, a lower collar revolvably mounted on the support and the fixed collar thereon, an upper collar revolvably mounted on the 75 upper end of the support, sweep arms projected from the lower collar and movable therewith, hangers pendent from the outer ends of the sweep arms, other hangers pendent from the inner ends of the said sweep 80 arms, an annular floor having an inner upturned flange that connects with the inner hangers and an outer upturned flange that connects with the outer hangers, radial partitions that extend from the inner to the 85 outer hangers, braces connected to the outer ends of the sweep arms and to the upper revolvable collar, a covering that extends over all of the said braces and forms a top 90 closure for all of the compartments, a fixed covering that extends over the inside of the inner hangers, and a series of covered doors, one for each compartment forming a peripheral closure for the compartments.

W. H. MARTIN.
